UNITED STATES PATENT OFFICE.

D. C. STOVER, OF LANARK, ILLINOIS.

IMPROVEMENT IN CULTIVATORS.

Specification forming part of Letters Patent No. 56,289, dated July 10, 1866.

To all whom it may concern:

Be it known that I, D. C. STOVER, of Lanark, in the county of Carroll and State of Illinois, have invented a new and Improved Cultivator; and I do hereby declare that the following is a full, clear, and exact description thereof, which will enable those skilled in the art to make and use the same, reference being had to the accompanying drawings, forming part of this specification, in which—

Figure 1 is a side sectional view of my invention, taken in the line $x x$, Fig. 2; Fig. 2, a plan or top view of the same; Fig. 3, a transverse vertical section of the same, taken in the line $y y$, Fig. 1; Fig. 4, a section of a portion of the same, taken in the line $z z$, Fig. 1.

Similar letters of reference indicate corresponding parts.

A represents a rectangular frame, which is mounted on two wheels, B B, and has a draft-pole, C, attached to it, and D D are two plow-beams, the front ends of which are fitted loosely on a shaft, E, at the under side of the front cross-bar, α , of the frame A.

The plow-beams D are connected in front of the axle F by links G, with arms or cranks b at the end of a shaft, H, said shaft having its bearings at the under side of the axle F, and provided at its center with a foot-piece or treadle, I, which projects behind the axle.

The beams D D have each an upright, e, attached, and the upper ends of these uprights are connected by a cross-bar, d, to which two pendent bars, J J, are attached by bolts e, the latter passing through any of a series of holes in plates f at the upper ends of bars J, in order to admit of the latter being adjusted higher or lower, as may be desired.

The two bars J J are connected by two bars, K K', the latter being secured to the former by pivots, and the bars K K' are connected together by a pivot, g, one bar, K', projecting considerably beyond K to serve as a handle, by operating which the bars J J may be moved toward and from each other.

The lower ends of the bars J J are attached to plow-beams L L, the front ends of which are secured to the front cross-bar, α , of the frame A by universal joints.

The rear parts of the beams D D L L have plow-standards M attached to them, as follows: The upper parts, α^x , of these standards at one side are made of semi-cylindrical form, and are fitted in concave sockets N, attached to the beams by bolts h, said bolts also securing the standards to the sockets by passing through slots i in the standards, said slots being of V shape, or gradually increasing in width from the outer to the inner sides of the standards, as shown in Fig. 4. This arrangement, it will be seen, admits of the plows N, which are secured to the standards, being turned so as to throw the earth either from or toward the plants, as may be desired, and said arrangement possesses the advantage of allowing the standards to turn back in case of the breaking of the braces j, the sockets N turning on the bolts h.

It will be seen that the plows of the beams L L may be readily moved laterally to conform to the sinuosities of the rows of plants by operating the lever K', and that all of the plows may be raised out of the ground when required for depositing the treadle I.

The device is extremely simple, and there are no parts liable to get out of repair or become deranged by use.

Having thus described my invention, I claim as new and desire to secure by Letters Patent—

The arrangement of the uprights e e and bar d with the pendent bars J J and plow-beams D D L L.

D. C. STOVER.
